UNITED STATES PATENT OFFICE.

DAVID CHARLES BOWEN AND JOHN FAIRFAX WALKER, OF JOHANNESBURG, TRANS-VAAL, SOUTH AFRICA.

MEANS FOR STEAMING AMALGAMATING-PLATES USED IN THE RECOVERY OF GOLD FROM ITS ORES.

1,334,333.

Specification of Letters Patent. Patented Mar. 23, 1920.

Application filed September 9, 1919. Serial No. 322,742.

To all whom it may concern:

Be it known that we, DAVID CHARLES BOWEN, a subject of the King of Great Britain, and JOHN FAIRFAX WALKER, a subject 5 of the King of Great Britain, both residents of Johannesburg, Transvaal Province, Union of South Africa, have invented certain new and useful Improvements Relating to Means for Steaming Amalgamating-10 Plates Used in the Recovery of Gold from its Ores, of which the following is a specification.

This invention relates to means for steaming amalgamating plates employed in the 15 recovery of gold from its ores, which operation is performed for the purpose of softening the amalgam which is former on the plate, in order to facilitate its removal therefrom usually by scraping.

20 The steaming of the amalgamating plates, as now effected, results in small quantities of mercury being carried off in the escaping steam, and thereby dispersed in the atmosphere. This causes mild forms of mercurial poisoning and deleteriously affects 25 the health of amalgamators and other persons engaged in plate houses or buildings where such operations are performed.

According to the practice presently adopted, 30 the plate which is to be steamed is covered, more or less completely, by means of a wooden box or cover placed over it and provided with an inlet for the steam. The sides of the cover are usually packed with 35 sacks or blanketing so as to prevent the escape of the steam, and retain it inside the box. As, however, the joints so packed are the only outlets for the steam, a large escape of the steam into the plate house or 40 building results. Except in particularly well ventilated plate houses the atmosphere is badly vitiated by the escaping mercury-laden steam, and when the cover is removed from the plate the evil is intensified due to 45 the passage into the atmosphere of the steam which is retained under the cover and also to the removal and handling of the steaming sacks, et cetera, used for the packing of the same.

50 Now the object of the present invention is to provide means wherein these defects are eliminated and thereby protect the operators

from the serious consequences thereof. As the adoption of the invention insures greater comfort for the operators and allows of the 55 work being done much more expeditiously it results in increased efficiency. Again, its use effects a saving in the quantity of steam necessary for the operation, as it results in an even distribution and concentration of 60 the same over the surface of the plate, and withal the cost of installing and operating the arrangement is small, particularly when considered in light of the advantages accruing to its use. 65

The invention will be fully described with the aid of the accompanying drawings wherein—

Figure 1 is a plan view of that portion of the arrangement which serves for inclosing 70 or covering the amalgamating plate, together with the connections thereto and the attachments for securing it in position above the plate; the plate and its supporting framework and the foot launder being 75 shown in dotted lines.

Fig. 2 is a section of Fig. 1 on line $x-x$.

Fig. 3 is a cross section of Fig. 1 on line $y-y$.

Fig. 4 is a cross section of the steam distributing pipe. 80

Fig. 5 is a diagrammatical representation in elevation of the apparatus adapted for use with a series of plates arranged in the well-known manner in two adjacent rows. 85

Fig. 6 is a diagrammatical representation in plan of the arrangement shown in Fig. 5, with the exhausting means removed.

In Figs. 1, 2 and 3 the amalgamating plate 1 and the framework 2 carrying said plate 90 are represented by dotted lines, and in Figs. 1 and 2 the foot launder 3, into which the pulp passes after flowing over the mercury-coated surface of the plate 1, is also shown in dotted lines. 95

In the accompanying drawings we illustrate that portion of the apparatus which serves for covering the amalgamating plate 1, constructed in two parts or sections. This will probably be found the most convenient 100 construction for amalgamating plates of large dimensions, although it is obvious that for smaller tables it may be constructed as a single part.

Each section of the cover for the amalgamating plate 1, comprises a top part 4, which may be in the form of a galvanized iron plate of suitable gage, and a supporting framework, consisting of an end member 5 and two side members 6, 7, which may be conveniently constructed of wood.

When the two sections of the cover are brought into position on the plate 1 they 10 form or provide immediately over the top of the plate 1, an inclosed chamber or space 8 whose width and length are practically equal to the corresponding dimensions of the plate 1, so that the latter is almost completely covered thereby.

Between the underside of the plates 4 and the members 5, 6, 7, of the supporting framework strips 9 of felt or any other suitable packing material are placed to form a 20 steam-tight joint. Around the edges of the plates 4 and on the top thereof there are placed straps or strips 10, of metal or any other suitable material, which, together with the plates 4 and the strips of felt or like 25 material 9 are secured to the members 5, 6, 7, of the framework by the bolts, screws or the like 11. As seen in Fig. 3 the heads of the bolts 11 are countersunk in the bottom edges of the members 5, 6, 7. On the bottom edges of the members 5, 6, 7, strips 12 of felt or other suitable resilient material are tacked or otherwise secured. When the 30 cover is in position on the plate 1 these strips 12 rest upon the upper surface of the 35 plate and preclude the escape of steam between the cover and plate.

Means are provided for making a steam-tight joint between the two sections of the cover when they are placed in position on 40 the top of the amalgamating plate 1, to preclude the escape of the mercury laden steam through said joint. The means shown for accomplishing this purpose consists of a bar or piece of wood or other suitable material 11^a secured to the underside of each of those edges of the plates 4 which abut when the sections are placed in juxtaposition. Between the top of the pieces 11^a and the bottom of the plates 4, strips 12^a of felt or the like are placed to form a steam-tight joint 45 between the said parts; and between the adjacent edges of the plates 4, the adjacent ends of the side members 6, 7, and the adjacent vertical surfaces of the bars or pieces 11^a, a strip of felt or like material 13 is placed to form a steam-tight joint between the sections of the cover. For the purpose of retaining the strip of felt 13 in position a strap or bar 14 is shown placed beneath 50 one of the pieces 11^a and projecting under the bottom of said strip 13. 15 is a piece of felt placed between the strap 14 and the bottom of the piece 11^a to prevent escape of steam between these parts. The bolts 16 55 which serve for securing the strap 10 on the

top of the one section of the plate 4, serve also for securing the felt strip 12^a, bar or piece 11^a, felt strip 15 and strap 14 to the bottom of the same section of the plate 4. 17 are bolts which serve for securing the strap 10 on the top of the other section of the plate 4 and also the bar or piece 11^a to the underside of the said section.

The sections of the cover are secured in position on the top of the amalgamating plate 1 by means of the clamping devices positioned at the outer ends of each section and at both sides of the joint formed between the sections. Each of the clamping devices consists of a member 18, which may so be of U or other suitable section, which extends across the cover from side to side. The ends, which project beyond the sides of the cover and framework 2 of the table, are slotted or bifurcated to be engaged by the 85 hook-shaped bolts 19. The hook-shaped extremities of the bolts 19 project under and engage with the framework 2—see Fig. 3—and have wing or fly nuts 20 screwed upon their threaded upper ends into engagement 90 with the tops of the slotted or bifurcated ends of the members 18. These clamping devices hold the cover down firmly on the top of the amalgamating plate and by the strips 12 of felt or the like, form a steam-tight joint around the edges of the cover 95 and the plate.

Each section of the cover is shown provided with two handles 21, 22, at each side. The portions forming the handles are carried by certain of the bolts 11. Those bolts which carry the handles 21, 22, are longer than the others and tubular distance pieces are placed upon them to support the ends of the handles.

The parts for making the steam supply connection to the cover are shown placed near one end of the cover. At this point a bar 23 or piece of wood or other suitable material is placed inside the cover beneath the plate 4, and a strip of felt or the like 24, is inserted between the bar and plate to make a steam-tight joint. The bar 23 at its ends may be let into the side members 6, 7 of the framework. A hole 25 is formed through the plate 4 and strip of felt 24 and bar 23, and extending through said hole is a piece of pipe 26, which is fixed to the said parts by means of the flange 27 and bolts 28. On the outer end of the pipe 26 a socket union or other suitable connection 29 is provided for attaching thereto the one end of a hose or other suitable preferably flexible pipe 30, which, at its other end is suitably connected to the main steam supply pipe 31—see Figs. 5 and 6. On the other and inner end of the pipe 26 a T piece 32 is fixed and into said T piece 32 there are screwed the perforated steam distributing pipes 33, 34—see Figs. 3 and 4. The other ends of 130

the pipes 33, 34 are closed by caps. These ends of the pipes 33, 34 are attached to the beam 23 and plate 4 by the U-shaped bolts 35, 36—see Figs. 1 and 3. As shown in Fig. 5 the steam distributing pipes 33, 34 are provided with three rows of holes to insure a more even distribution of the steam across practically the full width of the cover.

The parts for making the connection between the interior of the cover and the steam exhausting apparatus are shown positioned at the other end of said cover. The plate 4 at this point is additionally supported on the underside by means of two bars or pieces 37, 38 which are connected at their ends to the side members 6, 7 of the framework. In the plate 4 there is formed a circular hole 39, and around said hole there is riveted (as shown) or otherwise suitably fixed a member 40 which is of cylindrical shape in its lower portion and flanged at the bottom for the purpose of riveting it to the plate 4, and of truncated cone shape in its upper portion and flanged at the top for the purpose of attaching thereto or connecting therewith the one end of a hose or other suitable preferably flexible pipe 41, which at its other end is suitably connected to the main steam exhaust pipe 42.

30 In one of the end members 5 of the framework a hole 43 is preferably provided and fitted with a plug 44, for drawing off any water of condensation from the interior of the cover.

35 In the diagrammatical arrangement of the apparatus illustrated in Figs. 5 and 6, 45 indicates the plates of the one row and 46 the plates of the adjacent row. The main steam supply pipe 31 and the main steam exhaust pipe 42, extend between the rows 45, 46 at a suitable elevation. The pipe 31 is provided with a number of branches fitted with valves 47 for connecting the pipe 30 thereto in a convenient position, when the cover is used for any of the plates of the two rows. The cover is shown in position on one of the end plates so that the end valve 47 is then opened to admit the steam to the cover, and the other valves are closed. In like manner the exhaust pipe 42 is provided with a similar number of branches 48 for connecting thereto the pipe 41. Those branches 48 to which the pipe 42 is not attached are closed by blind flanges 49. The main steam exhaust pipe 42 connects (see Fig. 5) with an induction fan 50 whose outlet or delivery pipe 51 serves for conveying the mercury-laden steam outside the plate house or building and discharges into the open. 51^a is a valve for shutting off or regulating the passage from the pipe 42 to the inlet side of the fan 50.

Instead of or as an auxiliary to the fan 50 a steam or air operated ejector 52, fitted with 65 a valve 53, may be employed. If both de-

vices are provided, as shown in the drawings, then a valve 54 will be provided on the pipe 42 in addition to the valve 51, so that either the fan or ejector may be used independently of the other for exhausting 70 the steam from the interior of the cover.

In operating the arrangement the fan or ejector is put into operation and the steam admitted to the cover for a suitable length of time. When the steaming of the plate is 75 completed the steam is turned off, the flexible pipe 30 disconnected, from the main steam supply pipe 31, the clamping device removed and the plug which closes the water drainage aperture withdrawn. The fan or 80 ejector is preferably maintained in operation during these operations. One of the sections of the cover is now preferably slightly raised to allow air to enter the cover to carry away any remaining mercury-laden 85 steam. The connection with the steam exhaust pipe can now be broken and the cover removed and, if desired, placed on another plate and the connections remade and the latter plate be treated in a similar manner. 90

What we claim as our invention, and desire to protect by Letters Patent is:—

1. In apparatus of the nature indicated, the combination with an amalgamating plate of a cover therefor, means for introducing steam into said cover and means for exhausting mercury-laden steam from said cover. 95

2. In apparatus of the nature indicated, the combination with an amalgamating plate of a sectional cover therefor, means for introducing steam into said cover and means for exhausting the mercury-laden steam from said cover. 100

3. In apparatus of the nature indicated, the combination with an amalgamating plate of a cover therefor constructed in sections, means for making steam-tight joints between the sections of said cover and between the said cover and the plate, means for introducing steam into said cover and means for exhausting the mercury-laden steam from said cover. 105

4. In apparatus of the nature indicated, the combination with an amalgamating plate of a cover therefor, means for making steam-tight joints between said cover and said plate, means for introducing steam into said cover and means for exhausting mercury-laden steam from said cover. 115

5. In apparatus of the nature indicated, the combination with an amalgamating plate of a cover therefor, means for making steam-tight joints between said cover and said plate, means for introducing steam into said cover, means for exhausting the mercury-laden steam from said cover, and means for making steam-tight joints between the steam pipe and exhaust pipe connections with said cover. 125

6. In apparatus of the nature indicated, the combination with an amalgamating plate of a cover therefor, means for making steam-tight joints between said cover and said plate, means for introducing steam into said cover, means for exhausting the mercury-laden steam from said cover, means for making steamtight joints between the steam pipe and exhausting pipe connections with said cover, and means for clamping the cover in position on the plate.

In witness whereof we have each signed

our names to this specification in the presence of two subscribing witnesses.
